UNITED STATES PATENT OFFICE

CHARLES VALLONE, OF BUFFALO, NEW YORK

DESIGN FOR AN END FRAME FOR SWINGS OR SIMILAR ARTICLE

Application filed March 4, 1932. Serial No. 43,079. Term of patent 7 years.

To all whom it may concern:

Be it known that I, CHARLES VALLONE, a citizen of the United States, residing at Buffalo, Erie County, State of New York, have invented a new, original, and ornamental Design for an End Frame for Swings or Similar Article, of which the following is a specification, reference being had to the accompanying drawing, forming a part thereof.

In said drawing:

Fig. 1 is a perspective view of an end frame for swings embodying my design.

Fig. 2 is a sectional view thereof on line 2—2, Fig. 1.

I claim:

The ornamental design for an end frame for swings or similar article, substantially as shown.

CHARLES VALLONE.
